UNITED STATES PATENT OFFICE.

CHARLES C. LODER, OF CINCINNATI, OHIO, ASSIGNOR OF ONE-THIRD TO WILLIAM P. ANDERSON AND ONE-THIRD TO RICHARD K. LEBLOND, BOTH OF CINCINNATI, OHIO.

MECHANICAL STOKER.

1,329,617.

Specification of Letters Patent.

Patented Feb. 3, 1920.

Application filed June 30, 1917. Serial No. 177,985.

To all whom it may concern:

Be it known that I, CHARLES C. LODER, a citizen of the United States of America, and resident of Cincinnati, in the county of 5 Hamilton and State of Ohio, have invented a new and useful Improvement in Mechanical Stokers, of which the following is a specification.

An object of my invention is to produce a 10 mechanical stoker in which improved means are employed for agitating the coal, to prevent caking thereof and for feeding it across the grates.

A further object is to produce a mechanical stoker in which improved means are employed for controlling the movements of the various elements to regulate the feed of the coal and thereby to control the intensity of the fire.

20 A further object is to produce a stoker which requires less power to operate the elements thereof and in which the operation is more steady and uniform than other stokers known to me.

25 A further object is to produce a stoker in which an improved means for controlling the supply of air to the furnace simultaneously with the control of the supply of fuel thereto is provided.

30 These and other objects are attained in the stoker described in the following specification and illustrated in the accompanying drawings, in which;

Figure 1 is a front elevation of a stoker 35 embodying my invention mounted in position on a boiler setting which is shown in fragmental elevation.

Fig. 2 is a fragmental longitudinal sectional view of a stoker embodying my invention taken on line 2—2 of Fig. 1.

Fig. 3 is a fragmental transverse sectional view taken on the irregular line 3—3 of Fig. 4.

40 Fig. 4 is a sectional plan view of the stoker embodying my invention, the fuel hopper being removed to disclose certain portions of the construction which would be hidden thereby.

Fig. 5 is a fragmental side elevation of 50 the actuating mechanism of my improved stoker.

My improved stoker consists of a fuel feeding mechanism 6, a series of stationary

grate bars 7 located on each side of the fuel feeding mechanism, a fuel agitating mechanism 8 adapted to coöperate with the grate bars in the combustion of the fuel, a mechanism 9 for operating the fuel agitating mechanism, a clinker crushing mechanism 10 located on each side of the grate bars 7, 60 and an air feeding mechanism 11 controllable from the front of the boiler setting for furnishing the required amount of air to the fuel to aid its combustion upon the grate bars.

Fuel feeding mechanism 6 consists of a hopper 12 adapted to contain the fuel to be placed upon the grate bars, and a steam cylinder 13 containing a piston and piston rod 14 adapted to actuate a fuel pusher or plunger 15 located within the hollow casing 16 secured to the front of the boiler setting. Plunger 15 is adapted to be withdrawn by piston rod 14 to permit a charge of fuel to fall into position in front of it. Upon forward movement of plunger 15 the fuel located in front of it is pushed into a trough 17 which is substantially V-shaped in cross section as shown in Fig. 3. Passing longitudinally through the trough from one end to 75 the opposite end thereof is a rod 18 upon which a series of auxiliary fuel pushers 19 are mounted. These pushers are provided with somewhat abrupt front faces to facilitate the movement of the fuel from the front 80 to the rear end of the trough and their rear ends are made with a decided incline to permit them to pass beneath the fuel in the trough upon their return movement, so that the fuel rides over the pushers and drops into 85 the position back of them ready to be pushed through the trough toward the back thereof. Rod 18 is directly connected with piston rod 14 by means of a link 20 which is adjustably connected with an arm 21 extending downwardly from piston rod 14. Adjustable connection of link 20 with extension 21 is provided by means of a pin 22 removably mounted in a series of openings 23 formed in the link. An accumulation of fuel in 90 trough 17 causes the fuel to overflow the upper edges of the trough and on to the grate bars 7.

Grate bars 7 are secured to the edges of trough 17 by hooked extensions 24 which are 105 held in position with relation to the trough

by means of a plate 25 secured to the trough as disclosed in Fig. 3. The outer lower ends of the grate bars rest upon the upper edge of plates 26 which extend longitudinally of each side of the stoker frame and which rest at their ends in front and back plates 27 and 28 of the stoker frame. The grate consists of alternately arranged sets of bars 7^a and 7^b, bars 7^a containing openings through which are projected fuel pushers 29 and fuel stops 30. The series of pushers 29 constitute a fuel distributing mechanism. Bars 7^b are provided with openings adjacent to the trough, through which are adapted to be projected fuel agitators 31. The mechanism for operating agitators 31, pushers 29 and stops 30 consists of a series of arms 32, 33 and 34 connected with these respective elements and which are secured to the respective shafts 35, 36 and 37 which extend longitudinally of the furnace and journaled in front and back plates 27 and 28. Shafts 37 are adapted to be operated manually, being provided with squared ends 38 upon which suitable operating handles may be placed to cause stops 30 to be projected upwardly to stop the motion of the fuel when desired. Shafts 35 and 36 are however, connected with a mechanically actuated mechanism which causes their intermittent movement. Upon shafts 35 arms 39 are secured and upon shafts 36 arms 40 are secured. The arms of each set extend toward one another and are adapted to bear upon the hooked lower ends of bell crank levers 41 and 42 respectively. These levers are pivotally mounted at points 43 and 44 upon plates 45 which are reciprocally mounted upon the front of the boiler setting and which are held in position thereon by means of brackets 46. Between the lower arms of bell cranks 41 and 42 a pair of springs 47 are located for the purpose of maintaining the hooked ends of the bell cranks in engagement with arms 39 and 40. The upper outwardly extending arms of the bell cranks are adapted to be engaged by adjustable stops 48 and 49 which are provided for the purpose of tripping levers 39 and 40 at predetermined intervals of operation of the mechanism to permit agitators 31 and pushers 29 to return to their normal positions. Each of the upper outwardly extending arms of the bell cranks 41 and 42 is provided with a tooth 50 adapted to be engaged by the ends of a pair of pawls 51 and 52 pivotally mounted at points 53 and 54 on reciprocating plates 45. These pawls are for the purpose of disconnecting any desired element of the stoker from operative connection with the actuating mechanism. At the upper ends of the plates 45 lugs 55 and 56 are formed, pins 57 being located between these lugs and having the rear ends of bent levers 58 normally

in engagement therewith. Each of levers 58 is pivoted at a point 59 located at the side of casing 16 of the fuel feeding mechanism. The forward ends of levers 58 are upturned as disclosed in Fig. 5, and are adapted to be engaged by rollers 60 mounted on pins 61 extending from the sides of the piston rod. Thus when piston rod 14 is retracted to permit fresh fuel to fall from hopper 12, levers 58 are rocked upon their pivots 59 to elevate plates 45 and thus cause operation of fuel agitators 31 and fuel pushers 29 through their connected elements 41, 42, 39, 40, 55, 36, 32 and 33.

The clinker crushing mechanism located on each side at the outer ends of the grate bars, consists of a shaft 62 extending longitudinally from the front to the rear of the furnace, journaled in plates 27 and 28 and extending beyond the front plate of the boiler mounting. Each of these shafts has a ratchet 63 mounted at its forward end for co-operation with pawl 64 mounted upon a lever 65 extending toward plate 45 and connected therewith by means of a pin 66 mounted on the plate. Each shaft 62 is provided with a series of clinker crushing drums 67 which are secured to the shaft and are interlocked with each other as disclosed at 68 in Fig. 4. Adjacent to the drums a series of co-operating plates 69 are provided. These plates are hooked over a bar 70 embedded in each of the side walls of the brick setting of the boiler in such a manner as to pivot therewith. Back of each of these plates is a cam 71 mounted upon a shaft 72 extending longitudinally of the furnace and beyond the front plate of the boiler mounting as shown in Figs. 1 and 4, so that a crank handle may be applied to the squared end 73 thereof for the purpose of adjusting the positions of plates 69 with relation to the clinker crushing drums 67.

The air regulating mechanism of my improved stoker consists of an air conduit 74 having an outlet 75 located on each side of the back wall of the stoker and having its end opening upward as disclosed in Fig. 2. Each outlet is closed by a door 76 which is hinged at a point 77 to the back plate 28 of the stoker so that the door will close the opening tightly. Connected with each door is the end of a chain or cable 78 which passes over a pulley 79 secured to the rear plate 28 and which extends toward the front of the stoker, through plate 27 and the front boiler setting plate at a point 80, the forward end of the cable passing over another pulley at this point and an additional pulley 81 at a convenient point adjacent to the hopper 12. This end of each cable is connected to a pin 82 adjustably mounted in a slide 83 secured to the front plate of the boiler setting. By this means the degree of opening

of each door 76 may be regulated from the front of the boiler.

My improved stoker, as has previously been described, is arranged in two sections, 5 each of which may be rendered operative or inoperative by the pawls 51 and 52 at the front of the stoker. This is convenient in many ways and for the purpose of still further increasing this convenience I have divided the space beneath the grate bars, 10 which is provided as an ash receiving receptacle, with a longitudinally extending partition 84. This partition is of sheet metal and is convenient in that it separates the heat in one compartment from the compartment 15 beneath that portion of the stoker which may be idle, thus permitting of repairs and other adjustments being made on one side of the stoker without having to stop the operation of the opposite side thereof. In the front plate 27 a door 85 is located on each side of the partition to communicate with the ash pit. In Figs. 1 and 2 it will be seen that the front plate of the boiler setting does 20 not extend to the floor but is supported in such a manner that sufficient space is between it and the floor to permit of doors 85 being opened to allow ashes to be removed and workmen to enter the ash pit. On each 25 side of the ash pit the spaces beneath the crushing mechanisms are open to permit of the crushed clinkers being removed readily. Regulation fire doors 86 are provided for affording access to the grates 30 should manual firing have to be restored to and also for observation of the condition of the fuel beds located on the grates.

Having thus described my invention, what I claim is:

40 1. A mechanical stoker comprising a fuel feeding mechanism consisting of a hopper, a trough communicating with the hopper, a main fuel pusher located in the trough adjacent to the hopper, and a series of auxiliary fuel pushers located in the trough, a fuel 45 agitating mechanism consisting of a series of grate bars, and a series of agitators adapted to be projected through the grate bars and into engagement with the fuel located on the bars, a clinker crushing mechanism, and means adapted to operate the fuel feeding mechanism in alternation with the fuel agitating and clinker crushing mechanisms, said mechanisms being arranged to 50 operate upon the fuel in substantially the order named.

2. In a mechanical stoker the combination of a centrally located feed trough, grate bars upon opposite sides of the trough, a 55 partition located beneath the trough and dividing the space beneath it and the grate bars into two compartments, a set of agitators projecting through each set of grate bars, mechanism upon each side of the parti-

tion adapted to actuate the agitators, air 65 conduits communicating with each of the compartments, means in operative connection with each of the conduits for controlling the flow of air therethrough, and means for rendering either set of agitators inoperative, whereby the air may be cut off from one set of grate bars at the same time that the agitators therefor are rendered inoperative.

3. A mechanical stoker comprising a fuel 75 feeding mechanism consisting of a hopper, a trough communicating with the hopper, a main fuel pusher located in the trough adjacent to the hopper, a series of auxiliary fuel pushers located in the trough, a fuel 80 agitating mechanism, a clinker crushing mechanism consisting of a rotatively mounted crushing drum, and an adjustable plate mounted adjacent thereto, and means adapted to cause the fuel feeding mechanism to 85 operate upon the fuel in alternation with the fuel agitating and clinker crushing mechanisms.

4. A mechanical stoker comprising a fuel 90 feeding mechanism, a fuel agitating mechanism consisting of a series of grate bars, and a series of agitators adapted to be projected through the grate bars and into engagement with the fuel located on the bars, a clinker 95 crushing mechanism consisting of a rotatively mounted crushing drum and an adjustable plate mounted adjacent thereto, and means adapted to cause the fuel feeding mechanism to operate upon the fuel in alternation with the fuel agitating and clinker 100 crushing mechanisms.

5. A mechanical stoker comprising a fuel feeding mechanism consisting of a hopper, a trough communicating with the hopper, a main fuel pusher located in the trough adjacent to the hopper, and a series of auxiliary fuel pushers located in the trough, a fuel 105 agitating mechanism consisting of a series of grate bars, and a series of agitators adapted to be projected from the grate bars 110 and into engagement with the fuel located on the bars, a clinker crushing mechanism consisting of a rotatively mounted crushing drum and an adjustable plate mounted adjacent thereto, and means adapted to cause 115 the fuel feeding mechanism to operate upon the fuel in alternation with the fuel agitating mechanism and the clinker crushing mechanism.

6. A mechanical stoker comprising a fuel 120 feeding trough, a set of grate bars located on each side of the trough and having their ends adjacent to the trough supported by the edges thereof, the opposite ends of the bars being lower than the trough-engaging 125 ends, a partition located beneath the trough and dividing the space beneath the trough and grate bars into two longitudinally ex-

tending compartments, walls located at the lower ends of the grate bars, adapted to support the bars at these ends, and a series of fuel stops located at the lower ends of the bars, adapted to stop the passage of fuel over the bars, and manually operated means adapted to operate the fuel stops.

In testimony whereof, I have hereunto subscribed my name this 28th day of June, 1917.

CHARLES C. LODER.
